CYMBAL STAND

Josephus B. Thompson, deceased, late of Covington, Ohio, by K. E. Stade, administrator, Covington, Ohio, assignor to Columbia Broadcasting System, Inc., New York, N.Y., a corporation of New York

Filed Oct. 9, 1968, Ser. No. 13,920

Term of patent 14 years

Int. Cl. D17—04

U.S. Cl. D56—1

FIG. 2.

FIG. 3.

FIG. 4

FIG. 5.

FIG. 1 is a perspective view of a cymbal stand embodying the new design;

FIG. 2 is a side elevational view thereof;

FIG. 3 is a top plan view thereof;

FIG. 4 is a front elevational view thereof;

FIG. 5 is a bottom plan view thereof; and

FIG. 6 is an enlarged elevational view of one of the legs and the associated mounting means therefor.

What is claimed is:

The ornamental design for a cymbal stand, substantially as shown.
